Attorney

UNITED STATES PATENT OFFICE.

EDWARD PARRADEE, OF GRAND RAPIDS, MICHIGAN.

AUTOMOBILE-BUMPER.

1,355,773

Specification of Letters Patent.

Patented Oct. 12, 1920.

Application filed April 29, 1920. Serial No. 377,727.

To all whom it may concern:

Be it known that I, EDWARD PARRADEE, a citizen of the United States, residing at Grand Rapids, in the county of Kent and 5 State of Michigan, have invented certain new and useful Improvements in Automobile-Bumpers, of which the following is a specification.

My invention relates to improvements in 10 so called "bumpers" for use upon automobiles, and its objects are: first, to provide a two plate spring bumper with which the back plate will be continuous, and the front layer will be divided; second, to provide a 15 means whereby the ends of the divided part of the bumper cannot come in direct contact with each other, and, third, to provide a means whereby the approaching ends of the front layer will be held rigid and perfectly 20 safe from becoming detached from the strengthening elements.

I attain these objects by the mechanism and construction shown in the accompanying drawing, in which Figure 1 is an elevation of the bumper disconnected from an automobile. Fig. 2 is a plan of the same with the clamping elements in place. Fig. 3 is the same with the upper piece of the clamping element removed to show the form 25 of the edges of the strengthening or splicing plate. Fig. 4 is a perspective of the splicing plate. Fig. 5 is a transverse section of the bumper upon the line 5—5 of Fig. 1.

Similar numerals indicate similar parts 30 throughout the several views.

In the construction of this bumper I make the bumper, proper, of a single plate of metal having the back layer 1' continuous with a curve 5 at each end and the plate continued parallel with the back plate, as at 1, and the disconnected ends a short distance apart. I make the splicing plate of the same width as the bumper plate but short, and form an offset, as 7, at each edge thereof 40 that is designed to hold the ends of the front plate 1 of the bumper from being forced together.

I provide for rigidly and firmly tying the 45 ends of the front plate, and the splicing plate together by the use of duplicate top and bottom plates 3 having grooves in their adjacent faces for the reception of the edges of plates, as shown in Fig. 5, the front edges of said plates having grooves wide enough 55 to receive the ends of the front plate and the

splicing plate. These plates are held firmly clamped upon the bumper by means of bolts 4, substantially as shown in Figs. 1, 2 and 3.

6 represents the supporting arms by means of which the bumper is connected with the frame of an automobile, the manner of making such connections not being here shown as the same is in common use upon this class of bumpers, as is, also, the manner of connecting the supporting arms with the bumpers, as indicated by the bolts 8 or the clamping staples 9, shown in Figs. 2 and 3.

It is to be understood that the body of this bumper, like all bumpers of its class, is to be made of spring metal capable of withstanding all ordinary shocks that may be brought to bear upon it, as the sudden stopping of an automobile ahead without time to properly stop the automobile following.

With this bumper I have achieved several 75 advantageous features over other similar types of bumpers, as follows: First, I dispense with the necessity of punching, drilling or otherwise forming holes in the plates for securing the central strengthening elements; second, I provide a double spring plate bumper, the construction of which is as of a continuous, unbroken steel plate, thus greatly enhancing its resilient qualities without, in any way, detracting from its 80 symmetry or the artistic features of its construction, and, third, I can place the supporting arms 6 at any point upon the back plate of the bumper, thus rendering it an easy matter to adjust the bumper to any 85 style of automobile chassis. Thus, I am able to provide a stronger, more resilient and more readily adjusted bumper at much less expense than any other bumper of its class 90 now on the market.

95 What I claim as new in the art, is:

1. In a bumper for automobiles, a body made of flat spring metal plate bent to form loops at the ends, the back plate made continuous and the front plate divided at its longitudinal center and the ends spaced apart, the front plate and the back plate and loops equally spaced apart, a splicing plate having its edges offset at its longitudinal center to pass between the ends of the front plate, and means for securely connecting the splicing plate with the front plate and holding all rigidly connected.

2. In a bumper for automobiles, a body formed of a single spring metal plate bent 110

to form a loop at each end of the bumper and to space a front plate and a back plate an equal distance apart the entire length of the bumper, the front plate divided at its longitudinal center and the ends spaced apart, a splicing plate having the edges offset at its longitudinal center to pass into the space between the ends of the front plate, an upper plate and a lower plate having a groove in one side at one edge to pass over the edge of the back plate, and a groove at the other edge to pass over the ends of the front plate and the splicing plate, and bolts passed through said upper and lower plates securing them firmly upon the edges of the back plate, the front plate and the splicing

plate, and means for securing the bumper to an automobile.

3. In a bumper for automobiles, a body formed of a single spring metal plate bent to form a loop at each end and a front plate and a back plate equally spaced apart, the back plate continuous and the front plate divided at its longitudinal center and the ends spaced apart, means for securely connecting and firmly splicing the divided front plate, and securing arms secured to the back plate and longitudinally adjustable thereon.

Signed at Grand Rapids, Michigan, April 24, 1920.

EDWARD PARRADEE.
